CLAIM

The ornamental design for a charging station for portable electronic devices, as shown and described.

DESCRIPTION

FIG. 1 is a front right perspective view of a charging station for portable electronic devices showing our new design.

FIG. 2 is a front elevational view thereof.

FIG. 3 is a rear elevational view thereof.

FIG. 4 is a right elevational view thereof.

FIG. 5 is a left elevational view thereof.

FIG. 6 is a top plan view thereof; and,

FIG. 7 is a bottom plan view thereof.

The broken lines in the drawing figures depict portions of the charging station for portable electronic devices and form no part of the claimed design. The charging station for portable electronic devices is shown with symbolic breaks in its length. The appearance of any portion of the article between the break lines forms no part of the claimed design.
